X-RAY APPARATUS

Harold R. Austin, South Norwalk, Conn., assignor
to M. W. Kellogg Co., New York, N. Y., a cor-
poration of Delaware

Application March 22, 1933, Serial No. 662,042

11 Claims. (Cl. 250—34)

This invention relates in general to X-ray apparatus and in particular to the combination with X-ray apparatus of apparatus for treating the air that surrounds the X-ray apparatus to prevent interference with the normal operation of the X-ray apparatus.

It has been found well nigh impossible to operate X-ray machines, especially those of the character used in the examination of metal articles, continuously for any length of time during days when the relative humidity and/or the temperature of the air are comparatively high. The interruption in operation is due to the inability to obtain the necessary high tension values across the terminals of the X-ray tube or tubes. The inability to build up the necessary high tension values, it is believed, is due to leakage through the exposed as well as the insulated portions of the circuit of the machine and discharge through the overload arrangements at voltage values much below those at which the overload arrangements are set to discharge.

The leakage through the exposed portions of the circuit of the machine and the discharge through the overload arrangements is due, at least in part, to the high relative humidity of the air which so alters the dielectric constant of the air enveloping the X-ray machine that the conditions contemplated in its design cannot be attained. The increased ionization at the times mentioned is also a factor in altering the dielectric constant of the air. The effect of the increased ionization of the air is at all times appreciable because of the fact that X-ray machines, and especially those used in the examination of metal articles, are generally enclosed in housings which prevent circulation of the air. Thus the quiescent air around the overload arrangements and the exposed parts of the circuit of the machine may become very highly ionized and greatly alter the dielectric constant of such air.

The leakage through the insulated portions of the circuit of the machine is due to the material increase in the conductivity of the insulation due to absorption by the insulation of even comparatively small percentages of moisture. It is known that small increases in moisture content of insulation material increase the conductivity of such material out of all proportion with the increase in moisture content.

It has been found that dust in the air that envelopes the X-ray machines also interferes with their normal operation. Dust in the air changes the dielectric constant of the air much in the

same way as moisture does, and dust on the parts of the X-ray machines provides leakage paths. Dust in the air will produce the undesired results just mentioned at any relative humidity value of the air.

It is an object of this invention to combine with X-ray apparatus means for acting upon the air which envelopes the apparatus to prevent undesired changes in the dielectric constant of such air.

It is a further object of this invention to combine with X-ray apparatus means under the control of the apparatus for preventing undesired increase in the relative humidity of the air enveloping the apparatus.

It is also an object of this invention to combine with X-ray apparatus means for constantly circulating the air which envelopes the apparatus, the circulating means including means for removing dust from the air and means for deionizing the air.

Other objects and advantages of the invention will be apparent from a consideration of the following description taken with the accompanying drawing, in which

Fig. 1 is a front elevation of an X-ray machine and its housing illustrating the invention,

Fig. 2 is a view similar to Fig. 1 but showing a different arrangement of the control for the air dehumidifying means, and

Fig. 3 is an enlarged front elevation of the air treating device with a portion of its casing broken away to show its internal construction, and Fig. 4 is a fragmentary view similar to Fig. 2 showing another control arrangement for an air dehumidifying means.

For the purposes of this application the invention is disclosed in connection with an X-ray machine of the character used in the examination of metallic articles, it being of course, understood that the invention may be used with all types of X-ray machines and is not limited to the particular type of machine mentioned.

The X-ray machines of Figs. 1 and 2 are generally similar and each includes a transformer 1, a rectifying device 2, an X-ray tube 3, and a pair of spaced metallic spheres 4 which serve as an overload discharge device. As in the usual practice, each of X-ray tubes 3 is housed in a suitable protecting cylinder 5 which includes a window, not shown, for the passage of the X-ray beam. Each of the X-ray machines is contained in a housing 6. A partition wall 7 is provided in each of housings 6 to divide the internal space thereof into a machine compart-

ment 8 and an operator's compartment 9. The walls forming compartments 8 are preferably of such a nature to give the required protection.

Each of transformers 1 has its low side connected through cables 10 to a current supply and its high side connected through insulated conductors 11 to the input side of its rectifying device 2. In each of Figs. 1 and 2 the output side of the rectifying device 2 is connected through insulated conductors 12 to the terminals of X-ray tubes 3, and also through insulated conductors 13 to the pair of metallic spheres 4. The meters, switches, controls, etc., usually forming a part of such X-ray machines are located in compartments 9 and are generally indicated by numerals 14. No effort has been made to show the connections of meters, switches, controls, etc., 14 as such connections are well known and form no part of the present invention.

In each of Figs. 1 and 2 a unit 15 is shown as positioned beneath spheres 4 and between transformer 1 and rectifier 2. Units 15 serve to circulate, dehumidify, deionize, heat and remove the dust from the air in their respective apparatus compartments 8. Each of units 15, (see Fig. 3) includes a casing 16 having an air inlet 17 near its bottom and an air outlet, not shown, near its top. Within each of casings 16 is a dehumidifying coil 18, a fan 19 or similar air circulating means, a heating coil 20, a dust removing means 21, a pan 22 for catching the water separated from the air passed through unit 15 and a pipe 23 for passing this water to the sewer or other place of disposal. Baffle plates 24 assure the air passing through the whole of coils 18 and 20 and also serve to support fan 19. Coils 18 and 20 are preferably finned to provide extended contact surfaces for the air passing therethrough. Dust removing means 21 may be of any well known construction and may be of the filter type or of the oil film type. Cooled dehumidifying medium is circulated through coil 18 by means of pipes 25 and 26. Heating medium such as hot water or steam is circulated through coil 20 by means of pipes 27 and 28.

In Fig. 1 the valve 29 which controls the inlet to dehumidifying coil 18 is operated by a diaphragm 30 which is connected by capillary tube 31 to a settable humidity sensitive control device 32. The valve 33 which controls the inlet to the heating coil 20 is operated by a diaphragm 34 which is connected by capillary tube 35 to a settable temperature sensitive control device 36.

In Fig. 2 the valve 37 which controls the inlet to the dehumidifying coil 18 is operated by a diaphragm 38 which is connected by capillary tube 39 to a settable control device 40. Control device 40 preferably includes an air compressing means and voltage sensitive means for controlling the operation of the air compressing means. Control device 40 has its voltage sensitive means connected to spheres 4 through conductors 41. The valve 42 which controls the inlet to the heating coil 20 is operated by a diaphragm 43 which is connected by capillary tube 44 to a settable temperature sensitive control device 45.

The X-ray machine of Fig. 1 is operated as in the usual practice, however, prior to the commencement of operation the fan 19 of unit 15 is started to set up the desired circulation of the air in compartment 8, humidity sensitive control device 32 set to the desired relative humidity value, and temperature sensitive control device 36 set to the desired temperature value. Humidity sensitive device 32 is preferably set to maintain

the relative humidity of the air in compartment 8 well below the relative humidity value at which trouble is experienced, for instance, device 32 may be set to prevent the relative humidity from exceeding 50%. The temperature sensitive device 36 is preferably set to prevent the temperature of the circulated air falling below the average temperature for the particular season. Fan 19 will draw air into unit 15 through air inlet 17 and pass such air through dehumidifying coil 18, heating coil 20 and dust removing means 21 to the outlet of unit 15. From the outlet of unit 15 the air will pass upwardly and come into contact with spheres 4. After striking the top of compartment 8 the air will move to the opposite wall and from thence will be deflected back toward unit 15 and again drawn into unit 15. It is to be noticed that the circulation set up by unit 15 is such that dust free air is constantly circulated around all parts of the apparatus so that excessive ionization of the air around the exposed parts of the apparatus, for instance, spheres 4, is avoided. It is also to be noticed that the air in passing through unit 15 comes in contact with grounded closely spaced metal surfaces of extended area and in so doing is effectively deionized.

When the relative humidity is above the desired value, humidity sensitive control device 32 will through capillary tube 31 and diaphragm 30 open valve 29 to allow circulation of the dehumidifying medium through coil 18. The air in passing in contact with the fins of coil 18 will be cooled and some of the moisture thereof will be condensed. This moisture will separate out on the fins of coil 18 and fall into pan 22 from which it leaves the unit through pipe 23. The cooling of the air will be sensed by control device 36 which through capillary tube 35 and diaphragm 34 will open valve 33 to allow steam or other heating medium to circulate through coil 19 and thereby heat the air back to the desired temperature. Fan 19 is kept in operation as long as the X-ray machine is used.

The apparatus shown in Fig. 2 operates substantially as just described with the exception that control device 40 is set to open valve 37 when the voltage across the terminals of X-ray tube 3 falls to a predetermined value. The voltage value to which control device 40 is set is preferably a value at which the X-ray machine can be successfully operated but which is less than the optimum value.

Although in Fig. 2 control device 40 is shown as connected across spheres 4 it may be connected across any desired points on the high side of the circuit. Thus it may be connected across the input of rectifier 2 or across the output of transformer 1. Also if desired control 40 may include an element sensitive to current variations instead of an element sensitive to voltage variations and if so arranged may be connected to the input of transformer 1 as shown in Fig. 4. Other changes may be made without departing from the invention as defined in the appended claims.

I claim:

1. In combination with X-ray apparatus, a housing therefor, means for continuously circulating the air in said housing and means for modifying the moisture content of said air.
2. In combination with X-ray apparatus, a housing therefor, means for continuously circulating the air in said housing, means for removing dust from said circulated air, means for modi-

- fyng the moisture content of said air and means for heating said modified air.
3. In combination with X-ray apparatus, a housing for said apparatus, means for continuously circulating the air in said housing and means for preventing the relative humidity of said air from exceeding a predetermined value. 80
4. In combination with X-ray apparatus, a housing for said apparatus, means for continuously circulating the air in said housing, means for modifying the moisture content of said circulated air, and settable means adapted to control said moisture modifying means to prevent the relative humidity of said circulated air from exceeding a predetermined value. 85
5. In combination with X-ray apparatus, a housing for said apparatus means for continuously circulating the air in said housing, means for modifying the moisture content of said circulated air, settable means adapted to control said moisture modifying means to prevent the relative humidity of said circulated air from exceeding a predetermined value, means for heating said circulated air, and means adapted to control said heating means to maintain said circulated air at a predetermined temperature. 90
6. In combination with X-ray apparatus and the energy circuit therefor, a housing for said apparatus, means for continuously circulating the air in said housing, and means affected by changes in the energy flow in said energy circuit for preventing the relative humidity of said air from increasing to values at which the normal operation of said apparatus is interfered with. 100
7. In combination with X-ray apparatus and the energy circuit therefor, a housing for said apparatus, means for continuously circulating the air in said housing, means for modifying the moisture content of said air, and settable means affected by the energy flow in said energy circuit operable to control the functioning of said moisture content modifying means. 115
8. In combination with X-ray apparatus and the energy circuit therefor, a housing for said apparatus, means for continuously circulating the air in said housing, means for modifying the moisture content of said air, and settable means affected by the energy flow in said energy circuit operable to control the functioning of said moisture content modifying means. 120
- 125
- 130
- 135
- 140
- 145
- 150
- the energy circuit therefor, a housing for said apparatus, means for continuously circulating the air in said housing, means for modifying the moisture content of said air, settable means affected by the energy flow in said energy circuit operable to control the functioning of said moisture content modifying means, means, for heating said circulated air, and settable means for controlling the functioning of said heating means. 95
9. In combination with X-ray apparatus which includes an energy circuit and an X-ray tube, a housing for said apparatus, means for circulating air through said housing, means for modifying the moisture content of said circulated air, and means connected to said energy circuit at points at substantially same potential as terminals of said X-ray tube for controlling the functioning of said moisture content modifying means.
10. In combination with X-ray apparatus which includes an X-ray tube and an energizing circuit, a housing for said apparatus, means for continuously circulating the air in said housing, means for modifying the moisture content of said circulated air, and settable means connected to said energizing circuit at points substantially the same potential as the terminals of said X-ray tube for controlling the functioning of said moisture modifying means, said settable means being effected by voltage variations.
11. In combination with X-ray apparatus which includes an X-ray tube and an energizing circuit, a housing for said apparatus, means for continuously circulating the air in said housing, means for modifying the moisture content of said circulated air, settable means connected to said energizing circuit at points at substantially the same potentials as the terminals of said X-ray tube for controlling the functioning of said moisture modifying means, said settable means affected by voltage variations and means for heating said circulated air.

HAROLD R. AUSTIN.
